Primary Examiner — Elizabeth Abbert*Assistant Examiner* — Kelly Donnelly(74) *Attorney, Agent, or Firm* — Muncey, Geissler, Olds & Lowe, PLLC(57) **CLAIM**

I claim the ornamental design for a basket, as shown and described.

DESCRIPTION

FIG. 1 is a perspective view of the basket showing my new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The broken lines for the mesh show environmental structure and form no part of the claimed invention.
